(74) Attorney, Agent, or Firm — Harness, Dickey & Pierce, P.L.C.

(57) **CLAIM**

The ornamental design for a headphone with fans, as shown and described.

DESCRIPTION

FIG. 1 is a front elevation view of headphones with fans showing the new design;

FIG. 2 is the side elevation view of FIG. 1 thereof;
FIG. 3 is a rear elevation view of FIG. 1 in a folded condition thereof;FIG. 4 is a side elevation view of FIG. 3 thereof;
FIG. 5 is a front elevation of a second embodiment of the headphone with fans showing the new design; and,
FIG. 6 is a side elevation view of FIG. 5 thereof.
The broken lines to environment forms no part of the claimed design.**1 Claim, 6 Drawing Sheets**| (56)	References Cited
